UNITED STATES PATENT OFFICE.

GEORGE E. PARKS AND STEPHEN E. PARKS, OF PILLAGER, MINNESOTA, ASSIGNEES OF ONE-FOURTH TO HENRY I. COHEN, OF BRAINERD, MINNESOTA.

LUBRICATING ATTACHMENT FOR JOURNAL-BOXES.

1,177,207.

Specification of Letters Patent. Patented Mar. 28, 1916.

Application filed March 13, 1911. Serial No. 614,066.

To all whom it may concern:

Be it known that we, GEORGE E. PARKS and STEPHEN E. PARKS, citizens of the United States, residing at Pillager, in the county of Cass, State of Minnesota, have invented certain new and useful Improvements in Lubricating Attachments for Journal-Boxes; and we do hereby declare the following to be a full, clear, and exact description of the invention, such as will enable others skilled in the art to which it appertains to make and use the same.

This invention relates to lubricating attachments for journal boxes, and while we have shown it in connection with a car axle journal box, it will be understood that the principles involved may be embodied in an attachment to be used in any type of journal box or in connection with any journal to which it may be adapted.

The object of the invention is to provide a simple and efficient means for carrying the lubricating oil from the bottom of the box or other reservoir, to the journal in such manner as to insure a proper supply of lubricant at all times.

A further object of the invention is to eliminate the necessity for use of waste, felt, or other type of wick with their corresponding disadvantages.

A further object of the invention is to provide means for preventing splashing of the free body of lubricating oil.

In the drawings forming a portion of the specification and in which like numerals of reference indicate similar parts in the several views, Figure 1 is a section taken vertically and longitudinally of a journal box with the lubricating attachment therein, the journal, the lubricating roller and other parts being in elevation. Fig. 2 is a transverse vertical section through the journal box, the left hand portion of the attachment being in elevation while the right hand portion is in transverse vertical section. Fig. 3 is a section on line 3—3 of Fig. 2, the attachment being shown in top plan and the position of the journal thereabove being indicated in dotted lines. Fig. 4 is a perspective view of the combined lubricating roller support and baffle plate or anti-splasher. Fig. 5 is a vertical section taken longitudinally through the lower portion of a journal box with the journal in elevation, and

showing partly in section and partly in elevation the use of a modified form of lubricating or distributing roller. Fig. 6 is an elevation showing a further modification of lubricating or distributing roller.

Referring now to the drawings, there is shown a common type of journal box having upon the floor of the oil pit or container a plurality of upwardly directed studs 10, four in number, the box having the further additions of two ribs 11 which project from the side walls of the lower portion of the journal box at points midway of the length of the oil pit and extend to points somewhat short of the height of the lower face of the journal 12.

Instead of packing the oil pit with waste for carrying the lubricant to the journal, there is employed a lubricating or distributing roller 14 having trunnions 15 at its ends which are rotatably mounted in the bearings 16 and 17 of a supporting or carrying plate 18 which is in the form of a hollow frame. The plate or frame 18 has at one end the integral depending bearing 16 above referred to and at the opposite end the removable depending bearing 17 held to the under side of the frame by screws 19 or in any other suitable manner to facilitate ready application and removal of it.

As shown in Fig. 2 of the drawings and also in Fig. 3, the width of the opening 20 of the frame 18 is somewhat less than the diameter of the distributing roller while the length of the opening of the frame is slightly longer than that of the distributing roller, these last correlative dimensions permitting a slight longitudinal movement of the roller in the frame to meet corresponding longitudinal movement of the journal 8 in the journal box.

By reason of the width of the opening 20 being less than the diameter of the distributing roller and the fact that as shown in Fig. 2 of the drawings, the frame in practice lies above the axis of the distributing roller, it is necessary to apply the distributing roller to the frame from the bottom and it is because of this that the bearing 17 is made removable. It is of course understood that the trunnion at one end of the distributing roller is slid into the bearing 16, the rollers then raised into the opening of the frame and the bearing 17 is then adjusted under

the opposite trunnion and then fastened to the under side of the frame as above described.

In the sides of the frame are notches 21 5 which receive the ribs 11 respectively and by which engagement the frame is held against longitudinal displacement in the journal box, it being understood of course that when the frame is raised clear of the ribs it may be 10 drawn longitudinally from the box.

The frame or plate 18 is yieldably sustained with the distributing roller in contact with the journal 12, by means of helical springs 22 one of which is disposed at each 15 corner of the frame or plate with its lower end engaged over one of the studs 10 while its upper end receives a corresponding stud 23 that depends from the frame.

In use, lubricating oil is supplied to the 20 box in a free state and in a quantity sufficient to reach to any point up to the plate or frame 18, it being understood of course that there must be enough oil to permit the distributing roller to dip into it.

25 As hereinbefore explained, the width of the opening in the frame 18 is less than the diameter of the distributing roller and upon reference to Fig. 2 it will be noted that the side edges of the opening lie very close to 30 the surface of the roller. Thus, the frame or plate 18 effectively serves as a baffle and prevents splashing or surging of the oil and consequent waste through the end openings of the box.

35 It is found in practice that the springs 22 serve to hold the distributing roller in intimate contact with the journal so that the latter is supplied with oil in quantity sufficient to insure proper lubrication at all 40 times.

In Fig. 5 of the drawings there is shown a modification of the distributing roller in the form of a spring wire helix 25 the end portions of which are fixed to an axle 26 which 45 is journaled in a frame 27 supported upon springs 28 in the same manner as the structure hereinbefore described. In this form of roller the oil is supplied to the journal helically and the spring quality of the roller 50 is utilized to insure intimate contact with the journal under various working conditions. Furthermore, when the distributing roller is traveling at a high rate of speed, the oil that is taken up on the inner surface 55 of the wire of the helix, passes comparatively gradually to the outer surface and thus is not thrown off by centrifugal action

before it reaches the bearing brass illustrated at 29 in Fig. 2 and in Fig. 1, which brass is an element of the ordinary journal 60 box, as understood.

In Fig. 6 of the drawings, is shown a third form of distributing roller similar to that shown in Fig. 5, the modification being in the formation of the end convolutions in mutual contact, thus insuring a greater quantity of lubricant to the end portions of the journal where it is most needed, than to the intermediate portions.

It will thus be seen that there is provided 70 an attachment which may be used in various types of journal boxes and which will deliver oil to the journal in ample quantity under all conditions of use. Furthermore, the entire oil pit, with the exception of the 75 room occupied by the attachment, will be utilized to contain oil. Thus a greater quantity can be carried in the box than when waste is used, and refilling is more seldom required. This permits of positive sealing 80 of the box lid in place and the positive prevention of ingress of foreign matter, with the well understood advantages.

What is claimed is:

The combination with an axle, of an axle 85 box therefor adapted to receive lubricating oil, a flat plate located within the axle box beneath the axle and having a rectangular opening therein, means for retaining the plate from lateral movement in the box, the 90 ends of said plate having depending U-shaped sockets, an oil distributing roller of relatively greater cross diameter than the opening in the plate provided with studs at the end thereof adapted to seat in the sockets 95 whereby the roller is rotatably mounted in the plate with the major portion of the roller lying below the plate, the construction being such that the splashing and escaping of oil in undesired quantities above the plate 100 is avoided, and vertically disposed coil springs interposed between the underside of the plate and the bottom of the axle box and normally holding said plate in position to cause the roller to bear at its upper portion 105 against the axle.

In testimony whereof, we affix our signatures in presence of two witnesses.

GEORGE E. PARKS.
STEPHEN E. PARKS.
